UNITED STATES PATENT OFFICE.

KARL A. STRITTER, OF NAHANT, MASSACHUSETTS.

BOOT AND SHOE.

1,161,083.

Specification of Letters Patent. Patented Nov. 23, 1915.

Application filed March 2, 1915. Serial No. 11,528.

To all whom it may concern:

Be it known that I, KARL A. STRITTER, a citizen of the United States, residing at Nahant, in the county of Essex and State of Massachusetts, have invented certain new and useful Improvements in Boots and Shoes, of which the following is a specification.

My invention relates to boots and shoes generally but more especially to boots and shoes constructed with so-called artificial soles, that is, with soles made from material other than leather such, for example, as rubber.

15 The object of the invention is to provide an improved boot or shoe and particularly an improved boot or shoe having an artificial sole.

20 My improved boot or shoe comprises a sole that is made with a marginal slit or recess which provides a flap upon the tread side of the sole covering the stitches which fasten the sole to the upper part of the shoe and also covering a flexible reinforcing strip 25 which is laid into position within said slit or recess and through which the sole attaching stitches are passed, the flap being preferably cemented down on top of the reinforcing strip and stitches after the sole attaching 30 stitches have been formed.

With the constructions heretofore commonly employed in manufacturing shoes with artificial soles of rubber or the like, it has been found that the tension on the 35 thread during the stitching operation would cause the thread to cut its way completely or partially out of the awl or needle perforations made in the sole for the stitches and, moreover, the awl or needle would start a 40 cut or fracture that would extend or grow under the constant flexing the sole receives in use. Also the flexing of the sole and the strain brought upon the stitches while the shoe was in use caused the stitches to cut the 45 material of the sole thereby loosening the latter from the upper. The reinforcing strip of my improved shoe may be of any suitable material but it is preferably a tape 50 of textile material and when incorporated in the shoe it obviates the objections just referred to by preventing the stitches from cutting the material of the sole. Furthermore the flap on the sole not only shields the 55 stitches but it also conceals the reinforcing strip, the latter being an item of some importance. The strip and stitch covering

flap on the sole not only conceals the strip but it prevents the latter from becoming frayed through wear which would likely be the case were the strip in an exposed position 60 upon the tread side of the sole, particularly when a textile strip is used. Also the appearance of the shoe is greatly improved by having the strip concealed.

Other features of my invention are here- 65 inafter pointed out.

In the accompanying drawings:—Figure 1 is a plan view partly in section, of the bottom of a shoe embodying one form of the invention. Fig. 2 is an enlarged section on 70 the line 2—2 of Fig. 1. Fig. 3 shows a piece of tape such as may be used in carrying out my invention. Fig. 4 is a sectional view of the sole before it is applied to the shoe and before it has been trimmed. 75

Having reference to the drawings, A represents the artificial sole of my improved shoe. This sole A, which may be made from rubber, is formed with a slit a extending from a point back of the breast of the heel 80 forward along one side of the shank, around the forepart and thence rearward along the opposite side of the shank to a point just back of the breast of the heel. This slit is provided to accommodate a flexible reinforcing strip B, which is preferably a textile 85 tape although any other suitable flexible material may be used, and when said slit is formed in the margin of the sole a flap a' is simultaneously produced upon the tread side 90 of the sole.

During the operation of stitching the sole to the welt D of the upper portion of the shoe the flap a' is held back out of the path of the presser foot and needle either by being turned back by the presser foot as the latter advances or through any other suitable means. As the stitching operation progresses the tape B is delivered or guided into the recess formed by the slit just in 100 advance of the needle and presser foot so that the sole attaching stitches C pass through said tape as well as the sole A and welt D. After the sole has been stitched to the upper part of the shoe the flap a' is 105 folded and cemented down onto strip B so as to cover the latter and the stitches. The sole is then trimmed approximately upon the line x—y, Fig. 4 after which the heel E is applied. 110

When the heel E is applied to the sole the breast of the heel is forward of the ends of

the slit α and flap α' so that the latter is protected against wear and tear by the heel.

Herein I have shown my invention as embodied in a Goodyear welt shoe but without departing from my invention the same may be incorporated in other types or makes of boots and shoes. Furthermore, while I prefer to start and stop the slit α and strip α' at points just back of the breast of the heel, it is to be understood that I do not limit my invention in this respect and the slit and reinforcing strip may extend around the sole to any desired extent.

If desired the textile reinforcing tape B may be secured within the slit α by cement or otherwise before the stitching operation is started, but in practice it has been found convenient to have the presser foot of the sewing machine constructed to serve also as a tape guide by which the tape is laid into the slit just in advance of the needle as the sewing operation progresses.

By using a tape of textile material the former may be of the desired thinness and yet have the required strength.

What I claim is:—

1. As a new article of manufacture, a sole formed with a marginal slit to accommodate a reinforcing strip and provide a strip covering flap, and a strip of reinforcing material within said slit.

2. As a new article of manufacture, an artificial sole formed with a marginal slit to accommodate a reinforcing strip and provide a strip covering flap, and a reinforcing tape secured within said slit.

3. A boot or shoe having its sole made

with a marginal tape receiving slit which provides a tape covering flap upon the tread side of the sole; a flexible reinforcing tape secured within said slit, and covered by said flap, and sole attaching stitches sewed through said tape and also covered by said flap.

4. A boot or shoe having its sole formed with a marginal tape receiving slit which provides a tape covering flap upon the tread side of the sole; a tape of textile material within said slit and covered by said flap, and sole attaching stitches sewed through said tape and also covered by said flap.

5. A boot or shoe having a rubber sole with a marginal tape receiving slit which provides a tape covering flap upon the tread side of the sole; a flexible reinforcing tape within said slit and covered by said flap, the latter being cemented down onto said tape, and sole attaching stitches sewed through said tape and also covered by said flap.

6. A boot or shoe having an artificial sole made with a marginal tape receiving slit which provides a tape covering flap upon the tread side of the sole; a flexible reinforcing tape within said slit and covered by said flap, the latter being cemented down onto said tape, and sole attaching stitches sewed through said tape and also covered by said flap.

In testimony whereof I have affixed my signature, in presence of two witnesses.

KARL A. STRITTER.
